ELEVATING DEVICE

Samuel R. Shaw, Jr., Ivanhoe, Calif., assignor of
one-half to Rudolph R. Indermill, Visalia, Calif.

Application April 25, 1949, Serial No. 89,500

6 Claims. (Cl. 187—11)

1

This invention relates to elevating devices and more particularly to a portable and improved means for elevationally positioning a platform for the support of various objects or persons.

In agricultural uses the present platform is particularly adapted to support workers engaged in tree-pruning or fruit-picking operations. It is also adapted to support spray rigs, wind machines, or the like.

It is among the objects of this invention to provide a new and improved conveniently elevated platform of convenient working dimensions and simplified operating qualities.

Other objects of the invention are the provision of a mobile elevating device incorporating desired characteristics of improved unitary control, uniform qualities of operation, stabilized in all positions of elevation, which is safe in use, simple and foolproof in construction, and susceptible of ready mass production on an economical basis.

Other specific objects of the invention include the provision of a new and improved winch construction, new and improved winch operating and locking mechanism, and improved telescoping and telescope operating means for hoisting and/or lowering a platform supported thereon.

The invention also includes among its objects the provision of improvements in design, construction and operation over prior art devices heretofore contemplated for generally similar purposes.

With these and other objects in view, the invention consists in the construction, arrangement and combination of the various parts of the device whereby the objects contemplated are attained, as hereinafter set forth, pointed out in the appended claims, and illustrated in the accompanying drawings.

In the drawings:

Figure 1 is a side elevational view of a portable elevator embodying this invention.

Figure 2 is a fragmentary plan sectional view as taken on line 2—2 of Figure 1.

Figure 3 is a vertical sectional view taken as on a line 3—3 of Figure 1.

Figure 4 is a detailed fragmental view, in vertical section, of a telescoping member.

Referring more particularly to the drawings, an elevator designated generally by the numeral 10 comprises a frame 11 supported for movement over the earth upon a set of wheels 12 mounted in bearings 13.

A frame bed 14, like the upper frame portion 11, may be generally rectangular in plan view and may comprise longitudinally disposed side members 15 and 16, a front transverse member 17, and a similar transverse rear member 18. The

rear wheels are conveniently journaled on the rear transverse frame member and the front wheels steerably journaled on the front transverse frame member 17. A traction tongue 19 is employed to impart earth-traversing movement to the frame and to steer the front wheels in any suitable conventional or other manner.

Reinforcing intermediate transverse frame members 21 and 22 may be welded or otherwise secured to the side members 15 and 16, and parallel track members 23, 24, 25, and 26 may extend longitudinally of the frame between the intermediate transverse members 21 and 22 to which they are secured not merely for additional support for the frame but more specifically to serve as tracks for wheels, as 28, 29, 30 and 31, the latter having concave rims 32 complementary to the cylindrical top sides of the track members 23 through 26, respectively, upon which they are designed to be guided. The tracks and wheels may take other cooperative forms such as rails and flanged wheels, channels, and channel guided wheels, and other suitable forms without departing from the spirit and scope of the present invention.

The wheels are secured for rotation within yokes 35 attached to respective inclined operating arms 36, 37, 38, and 39. The first two of said operating arms 36 and 37 are pivotally secured on a horizontal axis by an upper transverse support rod 40 while the other two operating arms 38 and 39 are similarly pivotally secured as upon a corresponding parallel transverse rod 41. The operating arms 36, 37, 38 and 39 may be telescopic, if desired, and incorporate means for locking the same in telescopically extended or contracted positions as for successive stepped elevational positioning through increased elevational ranges.

The transverse rods 40 and 41 are secured as to the innermost 43 of a pair of telescoping elements 43 and 44 vertically extensible and slidably disposed within upwardly extending tubular frame members 45, 46, 47, and 48 positioned at each corner of the frame. The connection of the transverse rods 40 and 41 with the elements 43 may be alternative, as within yokes 50. Said rods may be held within the yokes as by tie rods 51 extending completely through the transverse elements 40 and 41 and held by nuts 52 and washers 53, or the bolts, as 51, may be welded to the ends of the rods whereby the same may be held in position within the yokes 50. Said yokes may be threaded or secured as by welding to the upper end 56 of the inner telescoping elements 43.

The upper ends 58 of the operating arms 36

through 39 may also be secured to their respective bars 40 and 41 by means of yokes 59. Or they may be welded directly to said bars and the pivotal movement of the arms may thereby be transmitted to them as rotating pivots. If the bars are non-rotatable, as first noted, the yokes 59 are rotatable upon the bars and may be held in horizontal spaced relationship by sleeves or other well-known devices including clamps and the like.

Any suitable platform 61 formed as with channel irons 62 along the sides thereof may be supported either removably or permanently upon the upper ends 65 of the yokes 59. The platform is steadied and the framework 11 made suitably rigid by any diagonal bracing 66 extending transversely of the frame and by similar diagonal bracing 67 extending longitudinally thereof.

Adjacent one end of the upper frame portion 11 and mounted upon a suitable bracket 70 including bearings 71 is a winch generally designated at 72 and comprising an axle 73 journaled in the bearing 71. A plurality of drums 78, 79, 80, and 81 may be individually keyed to the shaft 73. The drums correspond in number and are in longitudinal alignment with the track members 23 through 26 and the corresponding operating arms 36 through 39, respectively.

Each drum employs a cable 84 secured thereto at one end and having its other end secured as in an appropriate yoke 85 to the lower end of the operating arms 36 through 39, respectively, adjacent the wheels 28, 29, 30, and 31. The cables 84 connected to the operating arms 36 and 39 are connected directly between the winch and said arms but the cables connected to the arms 36 and 37 pass around pulley wheels 90 rotatably mounted in brackets 91 upon the rear side of the frame.

A large gear 95 is keyed to the shaft 73 in mesh with a smaller gear 96 having a crank handle 97 keyed thereto. The smaller gear is mounted upon a plate 98 secured to the bracket 70 or the frame. A detent 99 mounted as on a pintle 100 engages the teeth of the larger gear 95 to prevent relative counterclockwise movement thereof, as illustrated in Figure 1.

In operation, the elevator 10 is moved to a place of use as through connection with a tractor or by hand by means of the tongue 19.

Elevation of the platform 61 is accomplished by counterclockwise rotation of the crank handle 97 thereby directly turning the small gear 96 and the larger gear 95 and enjoying the benefit of a mechanical advantage dependent upon the relative gear sizes.

Counterclockwise rotation of the crank handle 97 is permitted by the detent 99 and results in clockwise rotation of the large gear 95 and of its shaft 73 and associated drums 78 through 81, thereby winding the cables 84, respectively, on the drums. The cable secured to the operating arms 38 and 39, acting directly, and those secured to the operating arms 36 and 37, acting indirectly, around the pulley wheels 90, draw the lower ends of the operating arms relatively together and into more vertical positions. During such movement the arms are pivoted around the axes of the respective transverse bars 40 and 41 to which they are secured, the wheels 28 and the like bearing against and being guided along the respective track members 23 through 26 upon which the weight of the platform 61 is sustained. In view of their connections, as aforesaid, and an absence of slack in the system, the cables turn

uniformly upon the drums of equal diameter raising the platform uniformly and easily.

The limit of upward extension of the platform is determined by the angle of inclination of the operating arms 36 and is limited by the length of said arms in their most vertical operative positions. In order to insure against axial separation of the telescoping elements 43 and 44, they may be provided anywhere along their length, 10 as at their lowermost ends, with annular shoulders 102 and 103, respectively, the latter being adapted to engage the former at a limit of upward movement of the innermost element 43 within the intermediate element 44. Corresponding shoulders 104 and 105 may likewise be arranged in complementary relationship for mutual abutment at a limit of upward movement of the intermediate telescoping movement 44 within the corresponding upright member 45.

When it is desired to lower the platform, the crank handle 97 may be slowly turned in a clockwise direction after releasing the detent 99 from its engagement with the large gear 95. The weight of the platform 61 and associated parts is then sufficient to cause return of the operating arms towards their less inclined position, decreasing the verticality of, and enlarging the angle made by, said arms, i. e., relative to the vertical members 45, etc.

It is not contemplated that the arms will be raised to a condition of absolute verticality or outwardly beyond the upright members 45, etc., inasmuch as such positioning would interfere with the automatic lowering of the platform.

If desired in lieu of or in addition to the detent 99, the interior of the upright members 45 and associated frame parts intercommunicating therewith as by means of the transverse members 21 and 22 and the longitudinal side frame members 15 and 16 may be rendered fluid-tight and filled with a hydraulic fluid, as oil, through any conventional one-way metering check-valve to permit the free vertical extension of the telescoping members by drawing such fluid from a reservoir through the valve in one direction but permitting a return to the reservoir and thus a lowering of the platform only slowly by means of such, as is accomplished by hydraulic jacks of conventional construction.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

The invention having been herein described, what I claim as new and desire to secure by Letters Patent is:

1. An elevator comprising a support frame, horizontally spaced vertical telescoping frame elements rigidly supported on the frame for upward extension, substantially horizontal track members arranged in the frame in alignment between the telescopic frame elements, track followers movable along said track members, said track members and followers having complementary surfaces for guiding said followers along said tracks, operating arms having first end portions pivotally secured to the upwardly extensible frame elements and second end portions secured to said track followers, and means for positioning the followers along their respective track members whereby their movement is translated

by their respective operating arms into responsive telescopic movement of their respective telescopic elements.

2. An elevator comprising a support frame, horizontally spaced vertical telescoping frame elements rigidly supported on the frame for upward extension, generally horizontal track members arranged in the frame in alignment between the telescopic elements, track followers movable along said track members, said track members and followers having cooperative association for guiding said followers along said tracks, operating arms having first end portions pivotally secured to the upwardly extensible frame elements and second end portions secured to said track followers, said operating arms respectively forming angles with said telescopic frame elements, winch means including cables connected to the second end portions of the operating arms for drawing said second end portions and said track followers along said tracks towards their respective telescopic elements to raise said telescopic elements, and a platform supported upon the upper ends of said extensible elements.

3. A portable elevator comprising a wheel-supported frame, horizontally spaced vertical telescoping frame elements supported on the frame for upward extension, said frame including generally horizontal track members aligned between the telescopic frame elements, track followers individual to the telescopic elements movable along said track members, said track members and followers having complementary surfaces for guiding said followers along said track, operating arms having first end portions pivotally secured to the upwardly extensible portions of the telescopic elements and second end portions secured to said telescopic elements' respective track followers, said operating arms respectively forming angles with said telescopic elements, means for imparting simultaneous corresponding movement to the followers relative to their respective telescopic elements, and a platform supported upon the upper ends of the telescopic elements.

4. A portable elevator comprising a generally rectangular wheel-supported frame, horizontally spaced vertical telescoping frame elements supported on the frame for upward extension at each corner thereof, said frame including generally horizontal track members in alignment between the telescopic elements, track followers individual to the telescopic elements movable along said track members, operating arms having first end portions pivotally secured to the upwardly extensible portions of the telescopic elements and second end portions secured to corresponding

track followers, said operating arms respectively forming acute angles with said vertical telescopic elements when said elements are telescopically retracted, winch means including a horizontal shaft rotatably mounted in the frame at one end thereof, means for rotatably positioning a shaft, and a platform supported upon the upper ends of said extensible elements.

5. In an elevator having a support frame, vertically extensible elements having a telescoping fit within the tubular frame members at each corner thereof, elevating means comprising generally horizontal track members mounted in the frame in alignment between said extensible frame elements, operating arms having first end portions pivotally secured to the upwardly extensible frame elements and second end portions secured to said track followers, and releasable means connected to the second end portions of the operating arms for drawing said second end portions and said track followers along said tracks towards their respective vertical members to raise said extensible elements.

6. In a portable elevator having a movable support frame, vertically telescopic elements rigidly mounted in spaced relation erectly in the frame, the combination of horizontal track members in alignment between said telescopic elements, track followers mounted for movement along the track members, operating arms having first end portions pivotally secured to the upwardly extensible telescopic elements and second end portions secured to said track followers, winch means including cables secured to the second end portions of the operating arms for drawing said second end portions and said track followers along said tracks towards their respective telescopic elements to raise said elements, and a platform supported upon the upper ends of said telescopic elements, said winch means comprising a horizontal shaft rotatably mounted in the frame at one end thereof, a gear keyed to one end of the shaft, means for rotating the gear and its shaft, detent means engageable with said gear to restrain unwinding movement of the winch means, said operating arms being in opposed slanting relationship longitudinally of the frame, pulleys guiding and reversing the effective pull of the cables secured to the operating arms pivoted to the telescopic elements most remote from the winch means for causing such operating arms to cooperate with the most proximately pivoted arms to raise said platform.
